(57) **CLAIM**

The ornamental design for an adjustable foot post base as shown and described.

DESCRIPTION

FIG. 1 is a perspective view of an adjustable foot post base showing my new design;

FIG. 2 is another perspective view thereof;

FIG. 3 is a top view thereof;

FIG. 4 is a right side view thereof;

FIG. 5 is a front view thereof;

FIG. 6 is a left side view thereof;

FIG. 7 is a bottom view thereof;

FIG. 8 is a back view thereof;

FIG. 9 is an exploded perspective view of the adjustable foot base of FIG. 1 showing the adjustable feet removed;

FIG. 10 is a cross sectional view taken in the direction of line **10-10** in FIG. 9;

FIG. 11 is an exploded perspective view of the adjustable foot base of FIG. 1 showing the adjustable feet in another position;

FIG. 12 is a cross sectional view taken in the direction of the line **12-12** in FIG. 11;

FIG. 13 is a top perspective view of the adjustable foot base of FIG. 1 with the feet adjusted; and,

FIG. 14 is a cutaway view along line A-A of FIG. 13.

The broken lines depict environmental subject matter that forms no part of the claimed design. The drawings show symbolic break-lines along the height of the adjustable foot post base. The break-lines and the space in between the break-lines form no part of the claim design. The cross-sectional lines and brackets are graphic symbols which form no part of the claimed design.
